[57] **CLAIM**

The ornamental design for a toy rattle, substantially as shown and described.

DESCRIPTION

FIG. 1 is a top plan view of a toy rattle showing our new design;

FIG. 2 is a side elevational view thereof;

FIG. 3 is a left-end elevational view thereof;

FIG. 4 is a right-end elevational view thereof;

FIG. 5 is a side elevational view thereof showing the design in a vertical condition; and,

FIG. 6 is another side elevational view thereof showing the design in an inverted vertical condition with respect to FIG. 5.
